UNITED STATES PATENT OFFICE.

LERoy B. TAYLOR, OF CLEVELAND, OHIO.

METAL WINDOW CASING.

Application filed July 31, 1922. Serial No. 578,600.

To all whom it may concern:

Be it known that I, LEROY B. TAYLOR, a citizen of the United States, residing at Cleveland, in the county of Cuyahoga and 5 State of Ohio, have invented certain new and useful Improvements in Metal Window Casings, of which the following is a specification.

This invention relates to metal windows, 10 and especially to the casings thereof, and has for its object to provide a casing which can be readily set in the wall and which will form a tight and weather proof joint with the sash, and at the same time provide a neat 15 appearance, and the casing is so constructed that it can readily be installed in place.

The casing is particularly suitable for windows of that type in which the sash are mounted between swinging arms so that the 20 sash can be reversed for the purpose of cleaning the same, or which can be opened to a greater or lesser extent. Such a window is shown in my Patents Nos. 1,267,745 and 1,267,746, to which reference may be 25 made for the details of construction.

In the accompanying drawings Fig. 1 is an inside elevation of the window, closed. Fig. 2 is a diagrammatic vertical section illustrating the movement of the sashes. 30 Fig. 3 is a horizontal section on the line 3—3 of Fig. 1. Fig. 4 is a vertical section on the line 4—4 of Fig. 1.

In the drawings the upper and lower sashes are indicated at B and D respectively, 35 each of these being pivoted at about the middle thereof, as shown at 30, to arms indicated respectively at A and C, the lower ends of the arms A and the upper ends of the arms C, being pivoted to the window 40 casing at 6 and 7 respectively, so that the sashes can be swung inwardly with the arms and then reversed between the arms to locate them inside out, in the manner described in said patents.

The details of the casing and sash will be 45 more fully apparent from the enlarged sectional views, Figs. 3 and 4. Each sash comprises an outer frame 8, L-shaped in cross section, with its flange 9 at the outside, and 50 an inner L-frame 10, secured thereto, the glass 12 being held between the flange 9 on the outer frame and the flange 11 on the inner frame, and the sash includes, at each side, a strip 13 which is spaced from the 55 member 8 by a spacing piece 14, forming a groove or grooves indicated at 15 which ex-

tend vertically in the faces of the sash frame. The lower bar of each sash has a depending lip 16 which on the lower sash forms a tight joint with the bottom of the casing, and on 60 the upper sash laps the joint between the sash, as indicated at 16a.

The casing comprises a metal channel frame having one leg at each side of the window and a connection across the top, said 65 frame having a flange 17 which rests against the masonry 18, an outer web 19, and an inwardly projecting flange 20 parallel to the flange 17, and this casing is completed by a stepped cross piece 21 which rests on the 70 sill or on cement 22 applied thereto at the bottom of the window opening. An interior metal finish 23 laps the flange 17 on the casing member, and the arms A and C are pivoted to this piece as indicated at 6 and 7 as 75 above described, a small channel strip 24 being set in between the sash and the casing to form a stop and guide for a connecting bar X, one of which is located at each side of the casing, and to which the sashes B and 80 D are pivoted as indicated at Z and Y respectively. Each bar X is an angle bar or plate having at its inner edge a flange 40 which works in a groove between the edge of the channel 24 and the flange 41 of the side 85 piece 23. This bar ties the sash together, so to speak, and also prevents the sash from falling out of the window. When the sashes are reversed the bars X slide up and down in their guides, and when the sashes are 90 closed the bars rest in parallelism with the two sashes, with their lower ends near the bottom of the casing, as shown in Fig. 1.

The member 23 has an interior flange 25 which forms the inner finish around the 95 casing. The bottom of the casing is finished inside by an angular member 26 which forms the inner sill or ledge, and which hooks over one of the steps or shoulders on the member 21, as indicated at 27.

The flange 20 of the casing projects into the groove 15 in the sash, when the windows are closed, as shown in Fig. 3, and thereby forms a tight joint, but when the windows are swung open this joint is broken by the 105 inward movement of the sash. A slight bead 19a on the casing member provides a good appearance, and the flange 20, where it enters the groove 15, forms in effect a weather strip and excludes dust and rain. The 110 casing does not obstruct in any way the inward swing or reversing action of the sash,

the member 23 providing a surface adjacent to the sash which is all in the same plane. Preferably, the brick or tile of the outer surface of the wall will project to form a shoulder around the window opening, as indicated at 30, and the frame is set against this shoulder, or against a filling of mortar at the joint, as indicated at 31.

I claim:

- 10 1. The combination with pivoted sashes, of a window frame comprising side bars of channel section, each bar having a flange 17 adjacent the wall and a flange 20 adjacent to the sash, a finishing member 23 extending from the inside of the wall and lapping the flange 17, and a channel strip 24 set between the sashes and the member 23, the sashes being pivoted to said strip.
- 15 2. The combination with a casing, of upper and lower reversible swinging sashes, 20 arms pivotally connecting the sashes respectively and the casing, and bars connected at their opposite ends to the ends of the sashes.

3. The combination with a casing, of upper and lower reversible swinging sashes, 25 arms pivotally connecting the sashes respectively and the casing, and bars connected at their opposite ends to the ends of the sashes, the casing having guide grooves in the sides thereof, and the connecting bars having flanges 30 slidable in said grooves.

In testimony whereof, I do affix my signature in presence of two witnesses.

LEROY B. TAYLOR.

Witnesses:

JOHN A. BOMMARDT,
EDWARD I. HOBDAY.
